ATTORNEY

UNITED STATES PATENT OFFICE.

GEORGE GARBETH, OF STOCKTON, CALIFORNIA.

PISTON-RING COMPRESSOR.

1,422,557.

Specification of Letters Patent. Patented July 11, 1922.

Application filed January 5, 1921. Serial No. 435,118.

To all whom it may concern:

Be it known that I, GEORGE GARBETH, a citizen of the United States, residing at Stockton, county of San Joaquin, State of California, have invented certain new and useful Improvements in Piston-Ring Compressors; and I do declare the following to be a full, clear, and exact description of the same, reference being had to the accompanying drawings, and to the characters of reference marked thereon, which form a part of this application.

This invention relates to improvements in piston-ring compressors, this class of device being particularly adapted to be used in connection with the assembling of gas engine pistons and cylinders, and forms a handy tool for all engine repair men, as well as for private owners who "take down" their own car engines at times.

The principal object of my invention is to provide a device of this character, that is, one by means of which the rings of a piston may be compressed or squeezed to allow of their being readily slipped into the cylinder bore in connection with the piston on which they are mounted, which is adapted to serve its purpose and function whether the pistons are to be inserted from the top or bottom of the cylinder block.

A further object is to provide a means for retaining the rings in their squeezed or compressed position even after the pressure of the hands on the device is removed, so that the latter, with the piston, may be laid down at will without the compressor dropping off.

The device may also be adjusted to take rings or pistons of different sizes.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective elevation of my device, showing the same in expanded position.

Fig. 2 is a plan view of the same, showing the compressing band contracted.

Fig. 3 is a fragmentary section through a handle, taken on a line 3—3 of Fig. 1.

Referring now more particularly to the

characters of reference on the drawings, the numerals 1 and 2 denote a pair of flat handles pivoted together intermediate their ends as at 3, the lower portions of these members being the longer and serving as the handles proper. They are also so connected that when the lower portions are spread, the upper portions are practically adjacent each other, while when the reverse conditions take place, the lower portions overlie each other.

The upper end of the handle 1 is pivoted to one end of a flexible metal strip 4 which lies in a plane parallel to the plane of the handles and is slidably projected through a guide sleeve 5 formed on the outside and adjacent one end of a relatively wide and thin metal band 6 of spring steel or similar material, this band projecting considerably beyond the edge of the strip 4 in the direction opposite to the handles.

The band 6 normally assumes a circular form, the end opposite that end having the sleeve 5 thereon overlapping the latter at all times so that the size of the circle formed may be altered, the amount of such overlap depending on the movement of the handles, as will be seen. The band 4 is provided with a plurality of orifices 7 adapted to engage with lugs 8 projecting outwardly from the band 6, the position of these lugs thereon being such that under no conditions of contraction of the band will said lugs come into contact with the end having the sleeve 5 thereon. The lugs and orifices are all evenly spaced, so that the band 6 may be manually manipulated so as to permit of the engagement of the orifices 7 with different ones at a time of the lugs, thus altering the size of the circle made by the band regardless of the movement of the handles, the range of movement of the latter being limited by the fact that the upper end of the handle 1 will bring up against the sleeve 5, the other handle 2 being pivoted on to this sleeve.

In operation it will be seen that when the handles 1 and 2 are drawn together at their lower ends, the upper ends are spread, causing relative movement between the sleeve 5 and the band 4, which passes therethrough, the latter straightening out beyond the sleeve as this movement progresses.

The spring material of which the band 6 is made exerts an influence tending to expand the same as soon as the pressure on the handles is removed, so in order to hold

- the band 6 contracted when desired a quadrant 9 provided with a slot 10 is formed with or attached to the handle 1 below the pivotal joint, through which slot a bolt 11 is slidable 5 and which passes through the other handle 2, there being a clamping nut 12 on the latter end of the bolt and a fixed head 13 on the other end thereof bearing against the quadrant.
- 10 By this means, the handles may be moved to any position, and while so held by one hand, the nut 12 may be tightened with the other to clamp the handles in position.
- On account of the projecting of the main 15 clamping band 6 above the sleeve lugs, handles, etc., for a considerable extent, this band may be inserted without interference into the flared or chamfered portion almost universally found in the lower ends of gas engine cylinders, so that the piston rings may 20 be held compressed until they pass into the actual cylinder bore. By inverting the position of the device relative to the piston, it may of course be used to place the pistons 25 into the cylinders from the top, when the latter have removable heads.
- The handles, extending as they do parallel 30 to the axis of the band and close to the latter, make it easier and handier for the mechanic to manipulate and hold the piston, since the 35 weight is almost directly in line with his arm instead of a considerable distance to one side as is the case when the handles extend away from or at right angles to the axis of the band. Also with my positioning of the 40 handles, the hand manipulating the same is always in the clear and will never interfere with the bottom or top surface of the cylinder block.
- 45 It will also be noted that once the device is assembled, no parts can fall apart, since the spread of the upper portion of the handles is purposely limited to be less than the length of the band 4.
- 50 From the foregoing description it will be readily seen that I have produced such a device as substantially fulfills the objects of the invention as set forth herein.
- While this specification sets forth in detail 55 the present and preferred construction of the device, still in practice such deviations from such detail may be resorted to and do not form a departure from the spirit of the invention, as defined by the appended claims.

Having thus described my invention what I claim as new and useful and desire to secure by Letters Patent is:—

1. A piston ring compressor comprising a split spring band whose ends normally overlap and shaped to form a circle, a pair of handles extending parallel to the axis of the band, one handle being directly connected to the band, and means between the other handle and the band and connected to both, and at a point on the band opposed to

the connection of the first named handle therewith, the handles being arranged to be manipulated in unison to alter the size of the band circle.

2. A piston ring compressor comprising 70 a split spring band whose ends normally overlap and shaped to form a circle, a pair of handles extending parallel to the axis of the band, one handle being directly connected to the band, and means between the 75 other handle and the band and connected to both, and at a point on the band opposed to the connection of the first named handle therewith, the band projecting above the termination of the handles for a considerable 80 distance.

3. A piston ring compressor comprising a split spring-band adapted to encircle a ring, a pair of handles pivoted together, one handle being directly connected to the 85 band, means between the other handle and band and connected to both, and at a point on the band opposed to the connection of the first named handle therewith, a quadrant on one handle projecting to one side to lie adjacent the other handle, and clamping means 90 between the last named handle and the quadrant.

4. A piston ring compressor comprising a split spring band whose ends normally 95 overlap and shaped to form a circle, a pair of handles pivoted together intermediate their ends and the upper ends being connected to the band at opposed points thereon, the normal tendency of the band being 100 to expand, a slotted quadrant on one handle projecting to one side to lie adjacent the other handles, a headed bolt passing through the slot and through the other handle, and a nut on the bolt arranged to be turned to 105 clamp the quadrant and handle together at will.

5. A piston ring compressor comprising a split spring band whose ends normally overlap and shaped to form a circle, a flexible band adjustably connected to the spring band on the outside thereof, a sleeve adjacent the outer end of the spring band through which the flexible band passes, and a pair of handles pivoted together intermediate their ends, the upper ends of said handles being respectively connected to the sleeve and to the end of the flexible band beyond said sleeve. 110

6. A piston ring compressor comprising a split spring band whose ends normally overlap and shaped to form a circle, a sleeve at the outer end of the band, a flexible band 115 slidable through the sleeve extending across the sleeve-end of the spring band and wrapping around the latter for a certain distance beyond such end, the flexible band being provided with a plurality of orifices, lugs projecting outwardly from the spring band and adapted to engage with certain 120

125

130

ones at a time of the orifices, and handle members pivoted together and connected at their upper ends to the sleeve and to the adjacent end of the flexible band respectively 5 and arranged to be manipulated to alter the distance between their points of connection with the sleeve and band, the spring-band acting to normally hold such points of connection adjacent each other.

10 7. A piston ring compressor comprising a split spring band whose ends normally overlap and shaped to form a circle, a sleeve at the outer end of the band, a flexible band slidable through the sleeve extending across 15 the sleeve-end of the spring band and wrapping around the latter for a certain distance

beyond such end, the flexible band being provided with a plurality of orifices, lugs projecting outwardly from the spring band and adapted to engage with certain ones 20 at a time of the orifices, and handle members pivoted together and connected at their upper ends to the sleeve and to the adjacent end of the flexible band respectively, the sleeve and flexible band being set down 25 considerably from the upper edge of the spring band and the handles extending parallel to the axis of the spring-band circle and away from the upper edge of the band.

In testimony whereof I affix my signature. 30

GEORGE GARBETH
